NOTE-SHEET-PERFORATING MACHINE.

1,280,691.

Specification of Letters Patent.

Patented Oct. 8, 1918.

Application filed January 3, 1914. Serial No. 810,137.

To all whom it may concern:

Be it known that I, BRUCE V. EDWARDS, a citizen of the United States, and a resident of the city of Newark, county of Essex, and State of New Jersey, have invented certain new and useful Improvements in Note-Sheet-Perforating Machines, of which the following is a specification.

My invention is concerned with machines for perforating note sheets for use on player pianos or similar musical instruments in such manner that the perforations formed shall correspond to the notes to be played, and it has for its object the improvement of machines of this character in numerous important respects, and with this in view, my invention consists in the parts, improvements and combinations hereinafter set forth and claimed.

In the drawings forming a part of this specification, and wherein the same reference characters are used to designate the same parts throughout, Figure 1 is a plan view of a machine embodying the preferred form of my invention. Fig. 2 is an end view of the machine shown in Fig. 1. Fig. 3 is a cross sectional view taken on line 3—3, Fig. 1, and Figs. 4 and 5 are detail views.

Referring first somewhat briefly to the more important features, reference letter *a* is applied to the strip of paper or like material to be perforated; *b* designates a punch, a series of such punches *b* being used corresponding in number to the total number of rows of perforations to be formed in the sheet, there being one punch for each of the keys of the piano or player, usually 88 in number; *c* designates the punch plate across which the paper *a* passes and which coacts with the punches *b* in forming the perforations; *d* designates one of the movable slugs which control the operation of the punches *b* and are individually connected as by a string or other connecting means *e* to suitable operating means, usually the keys of a piano, and *f* designates a constantly reciprocating plate for actuating the punches *b* through the intermediation of the slugs *d*. The means for intermittently feeding the paper *a* across the punch plate *c* comprise constantly rotating rolls *g*¹, *g*², and an intermediate roll *h*, and by means of these three rolls the paper is tightly held and advanced at a con-

tinuous rate and the beater *i* striking against the paper *a*, coöperates with the said rolls to 55 secure the necessary intermittent feed of the paper so that the same may be advanced a definite distance when the punches *b* are withdrawn, the beater *i* remaining stationary during the punching action including the 60 insertion and withdrawal of the punches.

Referring now to the various constructional and mechanical parts in greater detail, reference number 1 designates the machine base which may be of any convenient 65 form, and is preferably square or nearly so in general outline, in order to provide for the convenient arrangement of the various parts thereon. 2 designates the source of power, which may be conveniently supplied 70 by an electric motor as shown; 3 designates the drive shaft driven from the motor 2, and preferably connected therewith by means of a flexible coupling 4. This drive shaft is provided with journal bearings 5, 5, on the base plate 1, and carries a friction disk 6 which is preferably secured to the shaft 3 at the end thereof, a suitable thrust bearing 6^a being arranged to take the thrust of the friction disk 6. The shaft 7 which is provided 75 with suitable journals 8, 8, extends preferably at right angles to the shaft 3. On this shaft 7 is mounted the movable friction wheel 9 which contacts with the friction disk 6 and may be moved across the face thereof 80 by any convenient controlling means such as the elbow lever 10 provided with the pin 11 which works in the circumferential slot 12 in the collar 13 attached to the friction wheel 9 and which may be operated from any convenient point through the link 14 pivotally 85 attached to the arm 10¹ of the lever 10. With such arrangement the speed of the shaft 7 may be varied with respect to the speed of the driving shaft 3 at the will of the operator by adjusting the friction wheel 9 to contact with any desired portion of the face of the friction disk 6. The constantly reciprocated plate *f* is driven from the shaft 7 by means of eccentrics 15 which are received 90 within the circular openings 16 in the pitmen 17 pivotally connected at 18 to extensions 19 formed on the plate *f* for this purpose. The slugs *d* are interposed between the forward edge of the plate *f* and the 95 punches *b* and are provided with cutout por-

tions or slots d^1 which normally are opposite the forward edge of the reciprocating plate f so that the plate f is free to reciprocate therein without striking the slugs d or 5 operating the punches. The slugs d are provided with a longitudinal slot d^2 at the bottom and rest upon a bar d^3 which is provided with a cushion covering d^4 which may have the form of a piece of rubber tubing 10 surrounding the rod d^3 and which serves to deaden any noise which would otherwise be produced by contact between the slugs d and the rod d^3 . A suitable stop piece such as the bar d^5 is provided for limiting the forward 15 movement of the slugs d , and this bar d^5 is preferably seated upon an elastic cushioning means, as for example, the rubber plate d^6 interposed between the bar d^5 and its support. The punches b which are preferably 20 circular and are comparatively small being preferably about $\frac{3}{2}$ of an inch in diameter, are firmly set in thin flat heads b^1 having about the same thickness as the punches b and each of the punches b and heads b^1 is 25 guided in contact with the co-operating slugs d by means of the thin plates 20 which are interposed between each of the slugs and punches in the series and are secured together by means of a transverse rod 21 passing 30 through openings in the plate 20, suitable distance pieces 22 slightly thicker than the slugs d and punch heads b^1 being interposed between the adjacent plates 20 in order to hold the plates 20 sufficiently separated to 35 permit of the free movement of the slugs d and punch heads b^1 therebetween. The punch plate c is provided with a series of perforations c^1 for receiving the punches b and is also provided with a plate c^2 having 40 an opening c^3 which communicates with the punch holes c^1 and receives the punchings formed during the operation of the machine, the punchings which collect in this opening c^3 may be driven out by means of an air 45 blast, suitable connections (not shown) being readily provided for the purpose.

Means for positively retracting the punches are provided and as shown such means comprise a bar 23 connected to the plate f as by 50 being attached to extensions f^2 thereof, and the punch heads b^1 being provided with a shoulder b^2 against which the rearward edge of the plate 23 strikes on its return movement whenever any of the punches have been 55 advanced by reason of the corresponding slug d having been raised. The beater i is also operated directly from the shaft 7 and preferably through means connected with the constantly reciprocating plate f . This 60 beater i has preferably the form of a circular rod or bar extending transversely across the machine beneath the punch plate c and mounted upon the longer arms 24', 24' of two elbow levers 24, 24, one at each end 65 thereof. The bars 25, 25 are pivotally con-

nected to the shorter arms 24'', 24'' of the elbow levers 24, 24 as shown at 26 and at their opposite ends are provided with a slot 27 which receives the pin 28 which is secured to the plate f by any convenient means 70 which will provide for its adjustment thereon, the connection illustrated for this purpose being shown in detail in Figs. 4 and 5 and comprising a plate 29 slotted at 30 to fit over the rear edge of the plate f to which 75 it may be clamped as by means of the cap screw 31 passing through an enlarged opening 32 formed in the plate f and the adjustment of the plate 29 carrying the pin 28 with respect to the plate f being secured by 80 means of a set screw 33, which passes through a threaded opening 34 in the plate 29 and contacts with the edge of the plate f and which may be locked in adjusted position by means of the lock nut 35. The lost motion 85 created by the provision of the slot 27 in the bar 25 provides for the withdrawal of the punches b before the beater is operated to advance the paper as is clearly shown in Fig. 3. The paper feeding roll h in the construction shown is also driven from the shaft 7, the gearing for this purpose comprising a worm 36 on the shaft 7, and a worm wheel 37 which coacts with the worm 36 and is secured to the shaft 38 placed preferably parallel to and on the opposite side of the frame 1 from the shaft 3, and the roll h is driven therefrom by means of miter gears 39 and 40. The roll h drives the rolls g^1 , g^2 , held firmly in contact therewith by springs 41 100 and 42, by friction, the paper a passing between the roll h and the rolls g^1 , g^2 , and being firmly held by such frictional contact. The paper a is fed from a roll, being preferably delivered to the machine over rollers 105 43, 43^a, between the rolls 44 and 45, the rolls 45 being provided with rotary knives 46, 46 at each edge thereof for trimming the edges of the paper, over and across the punch plate c , beneath the beater i , around the upper roll g^1 and between the roll h and the lower roll g^2 , whence it is delivered over the delivery 110 plate 46.

For aid in holding the paper stationary during the punching action, I provide a bar f^4 which is spring mounted upon the return plate 23 and has a spring contact with the face of the punch plate c during the time that the plate f and the return plate 23 are advanced and while the punches which 115 are being operated are within the paper. This plate is, of course, withdrawn from contact with the punch plate c as soon as the punches are withdrawn from the paper so that it does not prevent the advance of 120 the paper in the machine at the proper moment.

The apparatus described operates as follows:

Power being supplied as by passing an 130

electrical current through the motor 2, the shaft 3 rotates, thus rotating the friction disk 6 and the friction wheel 9 and imparting rotation to the shaft 7 which speed of rotation may be varied by adjusting the friction wheel 9 in its various positions. The paper *a* is passed over the feed rollers 43, 43^a and over the trimming rolls 44, 45 by which its edges are trimmed to the proper 10 width, over and across the punch plate *c*, beneath the beater *i*, around the rollers *g*¹ and *h* and between the roll *h* and the roll *g*², and the roll *h* being rotated from the shaft 7 by means of the worm 36, worm 15 wheel 37, shaft 38 and bevel gears 39 and 40, pulls the paper forward at the desired speed which is regulated by means of the friction wheel 9. The oscillating plate *f* is continuously oscillated from the shaft 7 and so long 20 as all the slugs *d* remain in their lowermost or depressed position, the paper passes through the machine without any perforations being made therein. As soon, however, as any one or more of the slugs *d* are elevated, as may be done by means of the keys 25 of the piano or by the pneumatics of the player machine, or manually or in any desired way, the opening *d*¹ being no longer opposite the plate *f*, the plate *f* strikes 30 against the slug *d* and the punch *b* actuated thereby punches a hole through the paper. As the plate *f* is withdrawn the plate 23 which is secured thereto is withdrawn therewith, thus withdrawing the punches *b* from 35 contact with the paper and as soon as the punches *b* have passed out of the paper and the pin 28 has come into contact with the bar 25 at the end of the slot 27, it actuates the beater *i*, and the paper, by means of the 40 conjoint action of the beater *i* and the rolls *h*, *g*¹ and *g*², is advanced the necessary space for receiving the succeeding perforation, which space is preferably slightly more than the diameter of the punch openings so that 45 successive circular openings situated close together will be punched into the material of the paper so long as a slug *d* is raised. The provision of the slot 27 in the bar 25 makes it possible for the beater *i* to be raised 50 by the pull of the paper so that while the rolls *h*, *g*¹ and *g*² are operated to feed the paper forward continuously, the paper is not advanced at the punching point during the punching operation and the tension upon 55 the paper serves to elevate the beater which is mechanically depressed in the manner described as soon as the punching operation has been completed.

I have referred to my improved machine 60 hereinabove more especially as operating upon a single sheet of paper. It will be understood, however, that its usefulness is not limited to the perforation of a single sheet of paper at a time, as would ordinarily be practised in the original recording of a

composition, but that a number of sheets may be superimposed upon one another and passed through the machine together, and the machine may be used in this manner more especially for the purpose of making 70 a number of duplicates from a sheet already recorded, the slugs *d* being preferably operated for such purpose by pneumatic means as in the ordinary player piano.

While I have illustrated and described a 75 specific embodiment of my invention, in order that the same may be clearly understood, it is to be recognized that the same is for the purpose of illustration only and that my invention is not confined thereto, 80 but is as broad as my claims, and that numerous departures may be made from the specific construction shown within the scope of my invention without departing from my invention or sacrificing any of its advantages.

Having thus described my invention, what I claim is:—

1. In a punching machine, a series of punches, a vibrating member, a bar, a series 90 of slugs between said punches and said vibrating member, said slugs being provided with recesses for normally receiving said vibrating member and also provided with end recesses, said slugs resting over said bar 95 at their recessed ends, substantially as set forth.

2. In a punching machine, a series of punches, a vibrating member, and a series 100 of pivoted slugs movable longitudinally on their pivots and adapted to be interposed by such longitudinal movement between said vibrating member and the punches, substantially as set forth.

3. In a punching machine, a series of 105 punches, a series of pivoted, longitudinally movable slugs provided with notches, a vibrating member normally received in said notches but adapted to contact with and rock said slugs on their pivots against the 110 punches when said slugs are moved longitudinally, substantially as set forth.

4. In a punching machine, a series of punches, punch heads therefor, said punch heads being each provided with a shoulder 115 on one side, a vibrating plate, slugs adapted to be interposed between said plate and said punches and to thereby move said punches in the punching direction, and a bar connected to said plate and arranged on the 120 shouldered side of the punch heads for retracting said punches, substantially as set forth.

5. In a punching machine, a continuously 125 acting sheet feed, a series of punches, means for actuating the punches, means carried by the punch-actuating means for holding the sheet stationary during the punching operation, and means operated by said punch-actuating means and comprising lost motion 130

connections for advancing the sheet during the interval when the punches are withdrawn, substantially as set forth.

6. In a punching machine, a continuously acting sheet feed, a series of punches, means for actuating the punches, means carried by the punch-actuating means for holding the sheet stationary during the punching operation, a beater for advancing the sheet during the interval when the punches are withdrawn, and lost motion connections for operating said beater from said punch-actuating means, substantially as set forth.

7. In a punching machine, a continuously acting sheet feed, a series of punches, a vibrating member, means adapted to be interposed between said member and the punches to actuate the punches, punch retracting means, means carried by the vibrating member to hold the sheet stationary during the punching operation, means for advancing the sheet during the interval when the punches are withdrawn, and lost motion connections between said vibrating member and said sheet advancing means, substantially as set forth.

8. In a punching machine, a continuous sheet feed, a series of punches, a vibrating member, a series of slugs adapted to be interposed between said vibrating member and the punches, means carried by the said vibrating member for positively retracting the punches, and means operated from said vibrating member and comprising lost motion connections for advancing the sheet during the interval when the punches are withdrawn, substantially as set forth.

9. In a punching machine, a continuously acting sheet feed, a series of punches, a vibrating member, a series of slugs adapted to be interposed between said vibrating member and the punches, punch retracting means, means operated from said vibrating member for intermittently advancing the sheet, and means carried by said vibrating member for holding the sheet against movement during the punching operation, substantially as set forth.

10. In a punching machine, a sheet feed, a series of punches, a vibrating member, a series of slugs adapted to be interposed between said vibrating member and the punches, means carried by said vibrating member for positively retracting said punches, a beater for advancing the sheet during the interval when the punches are retracted, and operative connections between said beater and said vibrating member, substantially as set forth.

60 11. In a punching machine, a sheet feed, a series of punches, a vibrating member, a series of slugs adapted to be interposed between said vibrating member and the punches, means carried by said vibrating member for positively retracting said

punches, a beater for advancing the sheet during the interval when the punches are retracted, and lost motion connections between said beater and said vibrating member, substantially as set forth.

70 12. In a punching machine, a sheet feed, a series of punches, a vibrating member, a series of slugs adapted to be interposed between said vibrating member and the punches, means carried by said vibrating member for positively retracting the punches, means operated from said vibrating member for advancing the sheet during the interval when the punches are withdrawn, and means carried by the vibrating member for holding the sheet against movement during the punching operation, substantially as set forth.

80 13. In a punching machine, a rack composed of a series of parallel separated plates, punches and slugs received between said plates, a vibrating member for advancing said punches by striking against said slugs, and punch retracting means carried by said vibrating member, substantially as set forth.

90 14. In a punching machine, a rack composed of a series of parallel separated plates, punches and slugs received between said plates, a vibrating member comprising two separated parts, one behind said slugs and one in advance of the heads of said punches, the first portion thereof adapted to advance said slugs and thereby the punches, and the second portion adapted to retract said punches, substantially as set forth.

100 15. In a punching machine, a rack composed of a series of parallel separated plates, punches and slugs received between said plates, a vibrating member comprising two separated parts, one below and one above said plates, the lower portion being adapted to advance said slugs and thereby the punches, and the second being adapted to retract the punches, substantially as set forth.

110 16. In a punching machine, a rack composed of a series of parallel separated plates, punches and slugs received between said plates, a vibrating member comprising two separated portions arranged at opposite edges of said plates, the portion arranged at one edge thereof being adapted to advance said slugs and thereby the punches, and the portion at the opposite edge being adapted to retract the punches, substantially as set forth.

120 17. In a punching machine, a rack composed of a series of parallel separated plates, punches and slugs received between said plates, the said punches being movable longitudinally and the said slugs being movable across the direction of movement of the punches, a vibrating member normally out of contact with the slugs but adapted to contact therewith and actuate the slugs and thereby the punches when the slugs are

moved out of normal position, substantially as set forth.

18. In a punching machine, a rack composed of a series of parallel separated plates, 5 punches and slugs received between said plates, said punches being longitudinally movable and said lugs being movable across the direction of movement of the punches and also movable with the punches, and 10 means for driving the slugs against the punches to actuate the punches when said slugs are moved across the direction of movement of the punches, substantially as set forth.
15. 19. In a punching machine, punching mechanism, a continuous sheet feed, parallel bell cranks, a beater for intermittently advancing the sheet at the punching point borne between the longer arms of the bell 20 cranks, and links connected to the shorter arms of said bell cranks and connected to the punch-actuating means by a lost motion pin

and slot connection, thereby causing the beater to strike sharply against the sheet to advance it during the latter portion of the 25 retractile movement of the punch-actuating means, substantially as set forth.

20. In a punching machine, a continuous sheet feed, a beater, levers on which the beater is mounted, links connected to said 30 levers at points closer to their fulcra than the beater, a vibrating member, a series of punches, means whereby said punches are selectively actuated from said vibrating member, and lost motion connections be- 35 tween said links and said vibrating member.

In testimony that I claim the foregoing, I hereto set my hand, this 18th day of December 1913.

BRUCE V. EDWARDS.
